AIR MOISTENING AND CLEANING DEVICE

Filed May 12, 1925

INVENTOR.
Henry J. Schmitt.
BY Edward A. Lawrence,
his ATTORNEY.

UNITED STATES PATENT OFFICE.

HENRY J. SCHMITT, OF EMSWORTH BOROUGH, PENNSYLVANIA, ASSIGNOR OF ONE-HALF TO WILLIAM M. YOUNG, OF AVALON, PENNSYLVANIA.

AIR MOISTENING AND CLEANING DEVICE.

Application filed May 12, 1925. Serial No. 28,741.

The object which I have in view is the provision of a new and improved moistening device through which the air is drawn as it passes to the carburetter.

5 For this purpose I provide a container which is interposed in the carburetter air-supply, and in which is mounted an annular water-tank through the center opening or bore of which the air is drawn, wicks having one 10 end portion immersed in the water in the tank and being disposed in and across the central bore so that said wicks intercept the current of air and thus impart their moisture.

15 I also provide means for supplying water to said tank, and for maintaining the supply of water therein.

Again the air taken into the carburetter, especially in the case of a travelling vehicle 20 carries in suspension considerable dirt, dust and particles of other foreign matter, and it is of decided advantage to remove such foreign matter before the air is mixed with the fuel to form the charge.

25 For the purpose of purifying the air before it becomes part of the fuel mixture, I subject it to centrifugal forces which results in the precipitation of the foreign matter.

Thus I provide a chamber into which the 30 air is drawn at a point spaced above the bottom of the chamber, the air entering tangentially to the vertical axis of the chamber, thereby forming a substantially horizontal eddy which causes the precipitation of the 35 dirt, dust or other foreign matter to the bottom of the chamber.

The said chamber is preferably the container of the moistening device, the lower portion of the container being employed for 40 cleansing the air before it is moistened.

Other novel features of construction, and also of arrangement of parts will appear from the following description.

In the accompanying drawings, Fig. 1 is a 45 side elevation showing a carburetter with my improved air-moistener and cleaner installed in its air-supply; Fig. 2 is a vertical diametric section of the same on enlarged scale, and Fig. 3 is a horizontal section taken on the line III—III in Fig. 2.

1 represents the carburetter of an internal combustion engine. As a matter of illustration I have shown a well known type of carburetter having a gasoline-inlet tube 2, an air-inlet tube 3, and a fuel mixture exit 55 4 which is connected in the usual manner with the inlet manifold of the engine. However the particular construction or type of carburetter is not important nor does it form in itself any part of my present invention, 60 as the latter is applicable to any construction or type of carburetter.

5 is a container which may be of sheet metal and of cylindrical form. The bottom 6 of the container is preferably readily detachable. Thus I have shown it provided with an annular flange 7 which fits up within the container and is provided with outwardly extending pins 8 which engage angular slots 9 in the container walls as shown 70 in Fig. 1. Thus the bottom is placed in position and given a part turn to lock it in place, or is given a reverse turn to detach and remove it.

The lid 10 of the container is also preferably removable. Thus I have shown it provided with a depending annular flange 11 which fits down over the top of the container, and screws 12 are inserted through holes in said flange and screwed into threaded holes in the wall of the container.

The lid 10 is provided with an axially located port 13 into which extends the air-supply pipe 3 of the carburetter 1. If desired the port 13 and the pipe 3 may be 85 provided with threads for screw-engagement, as indicated in Fig. 2.

14 represents an annular, inclosed water tank of proper exterior diameter to fit down into the top of the container 5, being supported from below, as by the spaced apart brackets 15 secured to the inner walls of the container.

The cross-sectional shape of the tank is preferably the downwardly tapered or 95 wedge shape shown in Fig. 2, thus providing an axial throat 16 which converges upwardly from substantially the interior diameter of the container to that of the port 13 in the lid. The extremity of the tube 3 preferably 100

enters the upper end of the throat 16. The tank 14 is prevented from rotating or moving from its position relative to the container, as by means of a screw 17 extending 5 down through a hole in the lid 10 and screwed into a threaded hole in the top of the tank.

The tank is also provided in its top with a water-supply port 18 in which is fixed an 10 upwardly extending and interiorly threaded bushing 19. 20 is an exteriorly threaded nipple inserted through a hole in the lid 10 and screwed into the bushing 19. 21 is a pipe which has its end inserted into the 15 nipple 20 and which is connected to a supply of water, such as to the radiator tank, thereby insuring the tank of a full supply of water. The pipe 21 is preferably provided with a valve 22 so that the tank may be 20 replenished at intervals if thought more desirable.

23 represents a plurality of wicks of cotton or other suitable material, whose upper ends are inserted through holes 24 in the 25 upper wall of the tank 14 so as to be always immersed in water. The other ends of the wicks are led downwardly and across the throat 16 and are anchored in place, as by being inserted or clamped into collars 30 25 formed by bending the free ends of the brackets 15. The wicks are preferably secants to said throat and are distributed and disposed so that the air drawn up through the throat will be subjected to the 35 moisture of the wicks, absorbing the same before entering the carburettor pipe 3.

The air is admitted to the container 5 below the throat 16 and preferably somewhat above the bottom of the container. The 40 gradually upwardly converging character of the throat 16 reduces friction and facilitates the passage of the air.

By imparting to the air a whirling or eddying movement in the lower portion of 45 the container, the dirt, dust or particles of other foreign material carried by the air is permitted to be precipitated into the bottom of the container, and its accumulations may be removed at proper intervals by removing 50 the bottom 6.

I obtain this circulatory movement of the air by admitting it tangentially of the axis of the container, the inlet pipe 26 being arranged, as shown in Figs. 1 and 3 so that 55 the entering air forms an eddy before ascending into the throat 16.

The pipe 26 is connected to the air supply tube in the usual manner.

From the foregoing it is apparent that 60 the air is cleansed of the impurities held by it in suspension, and it is then moistened by passing through the throat 16 in contact with the wicks 23.

The wicks 23 swell when moistened and 65 thus seal the holes 24 so that there is no

escape of the water from the tank 14 except by capillary movement along the wicks, and thus there can be no excess of water supplied and the interior of the container is free from water.

70 My moistener and cleanser is of inexpensive construction and contains no part liable to wear or breakage. When required, the wicks may be quickly and easily replaced.

The device is of small compass and thus 75 does not take up valuable and limited space.

What I desire to claim is:—

1. In an air-moistener for an internal combustion engine, the combination of a container having a cover provided with a central aperture, means for admitting air into the lower portion of the container, an annular water tank mounted in the upper part of said container, the central bore of 80 said tank converging upwardly, the upper end of said bore being in alignment with said aperture and being connected to the air intake of the engine carburetor through said aperture, and a plurality of wicks having their ends immersed in the water contained 85 in said tank and their bodies disposed in said bore, so that the air drawn through said container and bore by the suction of the engine will be moistened by contact with said wicks.

2. In an air-moistener for an internal combustion engine, the combination of a container, means for admitting air at one end of the container, an annular water tank 90 removably mounted within the other end of the container, the axial bore of the tank forming the air outlet of the container, the inner wall of said tank converging upwardly and being provided with holes, and wicks having their ends inserted through 95 said holes and immersed in the water and their bodies disposed in said bore for the purpose set forth.

3. In an air-moistener for an internal combustion engine, the combination of a container, an annular water tank mounted in and occupying the upper end of the container, the bore of the tank forming the air outlet of the container, the wall forming 100 said bore converging upwardly and being provided with holes, air inlet means at the lower end of the container, said means comprising a conduit opening tangentially in 105 said container whereby gyratory movement is imparted to the air admitted into said container before it passes out through said bore, and wicks having their ends inserted through said holes and immersed in the water and their bodies disposed in said bore for the purpose set forth.

4. In an air-moistener for an internal combustion engine, the combination of a cylindrical container, an annular water tank mounted in and occupying the upper end 110 of said container, the bore of the tank forming 115

ing the air-outlet passage of the container and being connected to the air intake of the engine carburetor, wicks having their ends extending into the water in said tank and 5 having their bodies disposed in said bore to intercept the current of air, and air inlet means at the lower end of the container, said means comprising a conduit opening tan-

gentially in said container whereby gyratory movement is imparted to the air admitted ¹⁰ into said container before it passes out through said bore.

Signed at Emsworth, Pa., this 27th day of April, 1925.

HENRY J. SCHMITT.
